DECORATIVE GRILLE FOR A LOUDSPEAKER CABINET

Donald H. Palmquist, Newport Beach, Calif., and George R. Wagner, Los Angeles, Calif., assignors, by mesne assignments, to LTV Ling Altec, Inc., Richardson, Tex., a corporation of Delaware

Filed July 17, 1969, Ser. No. 18,236

Term of patent 14 years

Int. Cl. D14—99; D25—01
U.S. Cl. D26—14

FIG. 2

FIG. 1 is a perspective view of a decorative grille mounted on the front of a loudspeaker cabinet;

FIG. 2 is a fragmentary enlarged, front elevation of the lower, left corner portion of the grille as viewed in FIG. 1; and

FIG. 3 is a cross-sectional view of the portion of the grille shown in FIG. 2, taken along the line III—III of FIG. 2.

The broken lines are shown for illustrative purposes and form no part of the design.

We claim:

The ornamental design for a decorative grille for a loudspeaker cabinet, substantially as shown and described.
